UNITED STATES PATENT OFFICE.

LEONARD L. FROST, OF BARADA, NEBRASKA.

CAR-COUPING.

SPECIFICATION forming part of Letters Patent No. 445,279, dated January 27, 1891.

Application filed April 19, 1890. Serial No. 348,647. (No model.)

To all whom it may concern:

Be it known that I, LEONARD L. FROST, a citizen of Barada, in the county of Richardson and State of Nebraska, have invented certain new and useful Improvements in Car-Couplers; and I do hereby declare the following to be a full, clear, and exact description of the invention, such as will enable others skilled in the art to which it appertains to make and use the same.

My invention relates to an improvement in car-couplers, and has for its object to produce a car-coupler which shall be simple in construction and easy and effective in operation.

15 A further object is to provide an improved coupling-pin by means of which the link will be held in position to enter into a draw-head.

A further object is to produce a coupling-pin constructed and applied to a draw-head 20 in such a manner that it shall of itself, without the intervention of auxiliary devices, be automatic in the coupling operation.

A further object is to provide a draw-head with means for maintaining the link in a normal level position.

25 With these objects in view the invention consists in certain novel features of construction and combinations and arrangements of parts, as hereinafter set forth, and pointed out in the claims.

30 In the accompanying drawings, Figure 1 is a side elevation of the device. Fig. 2 is a plan view of the same. Fig. 3 is a longitudinal sectional view. Fig. 4 is a view illustrating a modified form of transverse bar. Figs. 35 5 and 6 illustrate modifications of the coupling-pin. Figs. 7 and 8 illustrate modifications of the invention.

35 A represents a draw-head, which in general construction is similar to draw-heads now commonly in use. Made in the center of the top and bottom of the draw-head are aligned perforations *a a' b b'*, and located within the draw-head upon the bottom thereof is a block 40 B, having a recess *c*, adapted to partially surround the perforation *b'*, for a purpose which will presently appear. Passing transversely through the draw-head in rear of the perforations *a a'* is a bar C, supported at its ends 45 in notches *d*, made in the walls of slots *d'* in the side walls of the draw-head, whereby said bar may be adjusted at different distances

from the bottom jaw of the draw-head. The transverse bar C is preferably made of spirally-twisted metal or in other manner to insure more or less elasticity, and is so located in the draw-head that a coupling-link D may be inserted beneath it and be maintained in a level position by means of said bar, whereby it will at all times be in position to enter 55 a draw-head with which it is to be coupled. By making the cross-bar of elastic metal it will readily adjust itself to links of different thicknesses without the necessity of further adjustment.

60 In lieu of the transverse bar D, of elastic metal, said bar may be made in the form shown in Fig. 4. In this form the bar is pivotally supported at its ends in one pair of notches in the walls of the slots *d'* and is 65 provided with a lip or flange *e*, adapted to project downwardly. With this form when the link enters the draw-head it strikes the lip or flange and is guided beneath the bar, the flange being elevated sufficiently to permit the link to pass under it. Thus links of varying thicknesses may be employed, the flange *e* being elevated to admit the link, and in all cases the flange will normally rest on the link.

65 Passing through the perforations *a a' b b'* is a coupling device or pin E. This device is preferably made in a single piece of substantially inverted-U shape, comprising the pin proper E' and a guide-rod E'', the pin being 70 adapted to pass through the perforations *a a'*, and the guide-rod E'' being adapted to pass through the perforations *b b'*. The guide-rod E'' is provided with a shoulder *f*, adapted when two cars are to be coupled to rest upon 75 the bottom of the draw-head at the top of the perforation *b'*, thus maintaining the pin E' elevated. With the notch as shown in Fig. 5 and the coupling-pin elevated, as in Fig. 1, when the link enters the draw-head it passes 80 under the transverse bar D and strikes the guide-rod E'' and disengages the shoulder *f*, thus permitting the pin to fall within the link.

85 By providing the block B in rear of the guide-rod when the link of another car strikes the guide-bar E'' the latter will be prevented from being bent or otherwise injured.

90 In the form of device shown in Fig. 1 the

shoulder *f* is made on the reverse side from the shoulder on the form shown in Fig. 5, and on the inner face of the pin near its free end a notch *g* is made and adapted to receive and hold the link in position for coupling, the weight of the pin holding the link up level until contact of an approaching draw-head is made, when the link is forced back, thereby being disconnected from the pin, whereupon the pin drops down into proper position. When the link is disengaged from the notch *g* in the pin, the pin drops down, said notch coming below the line of draft, thereby avoiding any weakening of the pin. With the shoulder *f* on the rear side of rod *E*, as shown in Fig. 1, the shoulder *f* is disengaged and the pin permitted to fall by the jarring of the draw-head, caused by the engagement therewith of the draw-head to which it is to be coupled.

In the form of pin shown in Fig. 6 the notch *g* is dispensed with, and in lieu thereof a notched block *h* is inserted in a slot in the end of the pin.

When it is not desired to couple the car, the pin may be made to enter a socket *F* in rear of the perforation *a'*.

I do not wish to restrict myself to the use of a single guide-rod, as more than one may be employed.

In the form of the invention illustrated in Fig. 8 the pin is provided at a point in or approximately in its center with a screw-threaded perforation. In proximity to the pin a guide-rod *i* is passed through this perforation in the draw-head and projects downwardly therefrom. A screw-threaded arm *j* projects at right angles to the rod *i* and is adapted to enter the perforation in the pin, which latter is made with a notch *k* near its lower end to receive a link, as previously explained. Another guide-rod *l* is passed through a perforation in the draw-head and projects upwardly therefrom, being provided at its lower end with a screw-threaded arm *l'*, adapted to enter the screw-threaded perforation in the pin.

In the form of the invention shown in Fig.

7 the guide-rod *m* is passed through perforations in the draw-head and made to project 50 above and below the same, being provided at a point between its ends with a screw-threaded arm *m'* to enter a similarly-threaded perforation in the pin.

Having fully described my invention, what 55 I claim as new, and desire to secure by Letters Patent, is—

1. The combination, with a draw-head having aligned perforations therein, of a coupling-pin and guide-rod adapted to pass through 60 said perforations, said guide-rod having a shoulder thereon, and a rigid block in the draw-head in rear of the perforations, substantially as set forth.

2. The combination, with a draw-head having openings or perforations therein, of a coupling-pin and connected guide-rod adapted to pass through said perforations, said guide-rod having a shoulder thereon for engaging the draw-head, and a link-supporting device 70 located in a vertical plane passing between the plane of the coupling-pin and the plane of the guide-rod, the said link-supporting device being supported at its ends in the sides of the draw-head, substantially as set forth. 75

3. The combination, with a draw-head having aligned perforations therein, of a coupling-pin passing through said perforations and a link-supporting device of elastic material passing through the draw-head and supported 80 at its opposite ends in the sides of the draw-head, substantially as set forth.

4. The combination, with a draw-head having aligned perforations therein, of a coupling-pin passing through said perforations, said 85 pin having a recess *g* on its rear face near its free end to receive one end of a link, substantially as set forth.

In testimony whereof I have signed this specification in the presence of two subscribing witnesses.

LEONARD L. FROST.
